Specification for Design.

Patented Mar. 15, 1921.

Application filed March 8, 1920. Serial No. 364,301. Term of patent 7 years.

To all whom it may concern:

Be it known that I, HERVEY S. WALKER, a citizen of the United States, residing at Rydal, county of Montgomery, and State of Pennsylvania, have invented a new, original, and ornamental Design for Conduit-Bushings, of which the following is a specification, reference being had to the accompanying drawing, forming part hereof.

Figure 1 is a perspective view of a conduit bushing, showing my new design.

Fig. 2 is a sectional view, and Fig. 3 a bottom plan view of the same.

I claim:

The ornamental design for a conduit bushing, as shown.

In testimony whereof I have hereunto affixed my signature this 5th day of March, 1920.

HERVEY S. WALKER.
